DFS 2038

Burton Hallory of New Haven Conn.

Letter Patent No. 2235-Dated March 14, 1865.

Design for a Door-Lock.

The article referred to in this Letter Patent and making part of the same.

That all whom it may concern:

Be it known that Burton Hallory, of New Haven in the County of New Haven and State of Connecticut, have invented and produced a new and original design for Door-Locks; and I hereby declare the following to be a full, clear and exact description of the same, when taken in connection with the accompanying drawings and the letter of reference marked thereon, and which said drawings constitute part of this specification, and represent:

Fig. 1, a face view, and in

Fig. 2, an end view.

My invention or design relates to the construction of the two faces of a double or Jaws-faced lock. Both faces are alike save the screw a, which does not appear on but one side. The rim b is moulded, and a moulding B around the edge of both faces, seen in fig. 2. A single boss around the spindle hole C, a double boss around the key hole D, a bead encircles each of the screw holes e, e, and d, and a bead F extending on the face from the hole e, e, as seen in fig. 1. This completes my design, which for purposes of designation I have styled "Builders Lock."

I claim and desire to secure by Letter Patent the herein described design for a double or jaws-faced lock.
